UNITED STATES PATENT OFFICE.

ARTHUR W. FERRIN AND ALBERT H. ACKERMAN, OF MASSILLON, OHIO.

DESIGN FOR A WHEEL.

52,312.

Specification for Design.

Patented Aug. 27, 1918.

Application filed May 16, 1916. Serial No. 97,944. Term of patent 14 years.

To all whom it may concern:

Be it known that we, ARTHUR W. FERRIN and ALBERT H. ACKERMAN, citizens of the United States, residing at Massillon, in the county of Stark and State of Ohio, have invented a new, original, and ornamental Design for Wheels, of which the following is a specification, reference being had to the accompanying drawing, forming part thereof.

The figure is a perspective view of a wheel, showing our new design.

We claim:

The ornamental design for a wheel, as shown.

In witness whereof we hereunto subscribe our names, as attested by the two subscribing witnesses.

ARTHUR W. FERRIN.
ALBERT H. ACKERMAN.

Witnesses:

M. McC. EVERHARD,
GEO. W. KRATSCH.
